Specification of Letters Patent. Patented June 21, 1921.

Application filed December 15, 1920. Serial No. 431,001.

To all whom it may concern:

Be it known that I, THOMAS SLOPER, a subject of the King of England, residing at Devizes, Wiltshire, England, have invented 5 certain new and useful Improvements in Presses, of which the following is a specification.

This invention is for improvements in or relating to presses, and has for its main 10 object to provide a press in which articles providing a cylindrical surface can be subjected to mechanical pressure.

According to this invention, the press comprises in combination a sub-divided 15 presser-plate for applying thrust to the article to be pressed, a thrust-plate situated behind the presser-plate to provide a purchase surface from which the presser-plate can be advanced, and an expansible chamber 20 situated between these two plates, which chamber has a flexible wall on that side which bears against the sub-divided plate, and is so constructed that fluid can be admitted to it under pressure.

25 The invention is particularly applicable to the manufacture of tires when these have been built up in band form on a cylindrical support. After building up, it is necessary to consolidate the tire-band, and for this 30 purpose a press according to the present invention is particularly suitable, and in such case the sub-divided plate takes the form of a number of bars arranged to constitute a sub-divided annular plate, which bars are 35 disposed so as to be parallel to the central throughway axis of the annular plate formed by them, and are guided to move radially relatively to the said axis, the expansible chamber is annular in form, is made to surround 40 the annular plate constituted by the bars, and the chamber itself is surrounded by an annular thrust-plate.

One preferred form of the invention will now be described in detail, by way of example only, with the aid of the accompanying drawings in which:

Figure 1 is a partial central sectional elevation of an annular press, the left half of the figure showing the press opened for the 50 insertion of a tire-band and its mold and the right half of the figure showing the press closed on to the tire band;

Fig. 2 is an end view of Fig. 1, the left and right halves of this view illustrating 55 the parts in the relative positions in which

they are shown in the corresponding halves of Fig. 1; and

Fig. 3 is a section on the line 3—3 of Fig. 1 but on a larger scale than that of Fig. 1 and showing only one of the guides 60 2 in position.

Like reference numerals indicate like parts in all the figures.

An annular thrust-plate or sleeve 1 is drilled radially at its edges to provide guide-holes for a series of guides 2 whereby the movement of a plurality of bars 3 constituting the sub-divided presser-plate is controlled. The bars 3 shown in the drawings are straight bars and lie side by side, the 65 longitudinal direction of the bars being parallel to the throughway of the sleeve or thrust-plate 1. Each bar 3 carries two guides 2, one at each end, and the bars are 70 assembled on the inner side of the annular 75 plate 1 with the guides 2 projecting through the guide-orifices in the edges of said plate. The guides 2 are provided with shoulders 4 to limit the radial movement of the bars in the outward direction, that is toward the 80 wall of the annular thrust-plate, and the ends which extend beyond the thrust-plate are surrounded by springs 6 which tend to hold them at the limit of their movement 85 in this direction. Mounted between the two plates so that it surrounds the presser-plate and lies within the thrust-plate, is an annular chamber 7 of flexible material, such as rubber reinforced with canvas, which 90 chamber, when inflated, would take a form 95 which would be more or less circular in cross-section, but it is of such dimensions that when placed between the plates and these are in the inoperative position, its cross-section is elongated. Means, for example supply pipes 8 and 9, are provided for connecting the interior of the chamber 100 at will with means for supplying fluid under pressure, and it will be appreciated that as fluid is admitted, the chamber will attempt to become circular in cross-section and will thus expand, and in so doing will thrust the bars 3, constituting the inner annular plate, radially inward.

The operation of this press is as follows: 105 The article to be consolidated, such as a tire-band 13, is carried by a cylindrical support or mold 11 placed within the sub-divided annular plate prior to the admission of fluid under pressure to the expansible chamber 110

2

7. During this part of the operation, the parts are in the position shown in the left half of Figs. 1 and 2. Fluid is then admitted to the interior of the chamber 7 with the result that the bars constituting the sub-divided plate are advanced by the pressure of that wall which bears against them, and in this manner are made to apply thrust to the article. The parts are then in the position shown in the right half of Figs. 1 and 2 and they remain in this position while the tire is vulcanized. To release the article, the fluid is allowed to escape from the chamber 7, and the spring 6 then returns the bars 3 radially outward, so that they now take up the position shown in the left half of Figs. 1 and 2. The article can be then be removed from the press.

It will be appreciated that the invention is not restricted to a press in which the plates are annular in form; for instance, the sub-divided plate could be employed to apply pressure to an irregularly shaped article which it is constructed to surround, and the bars might advance inwardly varying distances according to the shape of the article.

If desired, the surfaces of the bars such as 3 which engage the article to be pressed, may be shaped to conform to the configuration required for the surface of the article to be treated within the press.

When the sub-divided plate is annular and is intended for use with articles providing a cylindrical surface, the bars may be of such cross-section if desired that they will lie closely to one another along their whole length when advanced inward to the full limit of their intended travel. This is shown more clearly in Fig. 3 in which the bars 3 are shown in their advanced position.

Although the invention has been described as adapted to a press operating on the outside of a cylindrical surface for the purpose of applying radial pressure inwardly thereto, it will be obvious that the invention would include in its ambit a press arranged to apply radial pressure outwardly, the sub-divided plate in such case being disposed exterior to the thrust-plate.

The presser-bars 3 may be covered on the side which is toward the expandible chamber with thin metal plates 12 to prevent the flexible wall of the chamber from being forced between the bars. These plates extend parallel with the bars and each plate covers the spaces on opposite sides of the bar to which it is allotted.

To prevent the press from being injured should fluid-pressure be applied when no article is in the press, there may be used with the press a fluid-supplying chamber which only contains sufficient fluid to bring the presser-bars to the limit of their travel in the operative direction.

By the employment of a large number of narrow bars to form the sub-divided plate, it is possible to obtain practically true radial pressure at every position, and the spaces between the bars may be so narrow that for most purposes they prove of no disadvantage.

What I claim as my invention and desire to secure by Letters Patent is:—

1. In a press, the combination of a sub-divided presser-plate for bearing against an article to be pressed, a thrust-plate situated on the side of the presser-plate remote from the said article for providing a purchase surface away from which the presser-plate can be advanced, an expandible chamber situated between said plates, which chamber comprises a flexible wall arranged to bear against the sub-divided plate, and means to admit fluid under pressure to said chamber, substantially as described.

2. In a press, the combination of a sub-divided presser-plate for bearing against an article to be pressed, said plate comprising a plurality of bars arranged side by side in annular form, a thrust-plate situated on the side of the presser-plate remote from the said article for providing a purchase surface away from which the presser-plate can be advanced, an expandible chamber situated between said plates, which chamber comprises a flexible wall arranged to bear against the sub-divided plate, and means to admit fluid under pressure to said chamber, substantially as described.

3. In a press, the combination of a presser-plate for bearing against an article to be pressed, which plate comprises a number of bars arranged side by side to surround said article, a thrust-plate situated on the side of the presser-plate remote from the article for providing a purchase surface away from which the presser-plate can be advanced, an expandible chamber situated between said plates, which chamber comprises a flexible wall on that side which bears against said bars, and means to admit fluid under pressure to said chamber, substantially as described.

4. In a press, the combination of a sub-divided presser-plate for bearing against an article to be pressed, a thrust-plate situated on the side of the presser-plate remote from the said article for providing a purchase surface away from which the presser-plate can be advanced, each bar of said presser-plate being guided by said thrust-plate to move toward and away from the latter, an expandible chamber situated between said plates, which chamber comprises a flexible wall arranged to bear against the sub-divided plate, and means to admit fluid under pressure to said chamber, substantially as described.

5. In a press, the combination of a presser-

- plate for bearing against an article to be pressed, which plate comprises a number of bars arranged side by side to surround said article, a thrust-plate situated on the 5 side of the presser-plate remote from the article for providing a purchase surface away from which the presser-plate can be advanced, an expansible chamber situated between said plates, which chamber comprises a flexible wall arranged to bear against the 10 sub-divided plate, means to admit fluid under pressure to said chamber, and a plurality of cover-plates carried by said presser-plate, which cover plates are arranged each to close a gap which would otherwise 15 be left open between two adjacent bars on that side which is toward said expansible chamber, substantially as described.
- 15 6. In a press, the combination of a sub-divided presser-plate for bearing against an article to be pressed, which press comprises a plurality of bars arranged side by side in annular form to be situated in concentric relation to said article, the said bars being located parallel to the central throughway axis of said plate, a thrust-plate situated 20 concentrically with the presser-plate on the side thereof remote from the said article, means to guide the bars so that they can move radially in relation to said axis, an annular expansible chamber situated between said plates, which chamber surrounds 25 said bars and comprises a flexible wall on that side which bears against the said bars, and means to admit fluid under pressure to said chamber, substantially as described.
- 25 7. In a press, the combination of a sub-divided presser-plate for bearing against an article to be pressed, said plate comprising a plurality of bars arranged side by side in annular form, a thrust-plate situated on the 30 side of the presser-plate remote from the article for providing a purchase surface away from which the presser-plate can be advanced, an expansible chamber situated between said plates, which chamber comprises a flexible wall arranged to bear against the 35 sub-divided plate, means to admit fluid under pressure to said chamber, and a plurality of cover-plates carried by said presser-plate, which cover plates are arranged each to close a gap which would otherwise 40 be left open between two adjacent bars on that side which is toward said expansible chamber, substantially as described.
- 35 8. In a radial press, the combination with a cylindrical thrust-plate, of a plurality of bars arranged side by side parallel to the axis of said thrust-plate in annular form and constituting a sub-divided annular presser-plate concentric with said thrust-plate, spring-controlled guide means carried by each of said bars and guided by said thrust-plate for guiding said bars radially in relation to the longitudinal axis of said thrust plate, an annular expansible chamber situated between said plates, which 45 chamber comprises a flexible wall on that side which bears against the bars, means to admit fluid under pressure to said chamber, and a plurality of cover plates carried by said presser-plate, which cover plates are 50 arranged each to close a gap which would otherwise be left open between two adjacent bars on that side which is toward said expansible chamber, substantially as described.
- 45 9. In a radial press, the combination with a cylindrical thrust-plate, of a plurality of bars arranged side by side parallel to the axis of said thrust-plate in annular form and constituting a sub-divided annular presser-plate concentric with said thrust-plate, spring-controlled guide means carried by each of said bars and guided by said thrust-plate for guiding said bars radially in relation to the longitudinal axis of said thrust plate, an annular expansible chamber situated between said plates, which 55 chamber comprises a flexible wall on that side which bears against the bars, means to admit fluid under pressure to said chamber, and a plurality of cover plates carried by said presser-plate, which cover plates are 60 arranged each to close a gap which would otherwise be left open between two adjacent bars on that side which is toward said expansible chamber, substantially as described.
- 55 10. In a press, the combination of a sub-divided presser-plate for bearing against an article to be pressed, which press comprises a plurality of bars arranged side by side in annular form to be situated in concentric relation to said article, the said bars being located parallel to the central throughway axis of said plate, a thrust-plate situated 65 concentrically with the presser-plate on the side thereof remote from the said article, means to guide the bars so that they can move radially in relation to said axis, an annular expansible chamber situated between said plates, which chamber surrounds 70 said bars and comprises a flexible wall on that side which bears against the said bars, and means to admit fluid under pressure to said chamber, substantially as described.
- 70 11. In a press, the combination of a sub-divided presser-plate for bearing against an article to be pressed, said plate comprising a plurality of bars arranged side by side in annular form, a thrust-plate situated on the 75 side of the presser-plate remote from the article for providing a purchase surface away from which the presser-plate can be advanced, an expansible chamber situated between said plates, which chamber comprises a flexible wall arranged to bear against the sub-divided plate, means to admit fluid under pressure to said chamber, and a plurality of cover-plates carried by said presser-plate, which cover plates are arranged each to close a gap which would otherwise be left open between two adjacent bars on that side which is toward said expansible chamber, substantially as described.

In testimony whereof I affix my signature.

THOMAS SLOPER.
